UNITED STATES PATENT OFFICE.

THEODE GARCEAU, OF THREE RIVERS, QUEBEC, CANADA.

BUCKLE.

1,394,195.

Specification of Letters Patent. Patented Oct. 18, 1921.

Application filed May 16, 1921. Serial No. 469,952.

To all whom it may concern:

Be it known that I, THEODE GARCEAU, a British subject, residing at #66 St. Thomas street, in the city of Three Rivers, in the 5 Province of Quebec, in the Dominion of Canada, have invented certain new and useful Improvements in Buckles; and I do hereby declare that the following is a full, clear, and exact description of the same.

10 The present invention relates to improvements relating to buckles and the main object of this invention is to provide a device of this character that will be of simple construction and particularly cheap to manufacture.

15 The invention will be better understood with the aid of the accompanying drawings forming part of this application, in which:—

20 Figure 1 is a perspective view of an arm band to which is adapted the invention.

Fig. 2 is an enlarged plan elevation of the buckle.

25 Like numerals of reference indicate corresponding parts in each figure.

Referring to the drawings, 1 indicates an arm band provided at one end thereof, with a folded fastening portion 2, and at its other end with the buckle 3; the buckle consists 30 of a plate having a strap or band receiving slot 4, said slot 4 being divided intermediate thereof by two inwardly projecting lugs 5 forming on one side of said slot 4 a strap-recess 6, within which is permanently secured one end of the arm band 1. The said 35 plate is also cut to form a passage 9 said passage communicating with a slotted portion 4.

30 In order to lock said arm band or strap in said slot 6, the lugs 5 are crushed against said strap or band, thereby preventing the displacement of the same. Opposite said recess 6 and collateral thereto, is provided slots 7, having at its lower end an inwardly 45 projecting lug 8, said lug 8 being preferably distanced from the lower lug 5 in order to provide a central passage 9 of the arm band.

It will readily be seen that the looped end of the arm band when inserted through the 50 opening 9 will enter the recess 7 and project

in between the lug 8 and the edge of said recess, thereby locking therein to prevent displacement. The motion of the arms will not unhook the said loop 2 from the buckle, as to unfasten the loop 2 from the buckle, 55 the buckle must be lowered in order that the lower edge of the loop 2 will clear the lug 8.

The form herewith disclosed could be slightly modified without departing from the spirit or scope of the invention. 60

What I claim as my invention is:—

1. A buckle comprising a plate provided with an inner recess; inwardly projecting lugs provided intermediate of said recess, said lugs being adapted to form a strap receiving slot; a lug inwardly projecting from the lower edge of aforesaid recess, and suitably distanced from said other lugs, a part of said plate between said last named lug and said other lugs being cut out, whereby a 70 passage is formed intermediate of the lower edge of said plate, said inwardly projecting lug forming a locking element for the loop provided on the other end of the strap, substantially as described. 75

2. A buckle comprising a plate provided with an inner recess; inwardly projecting lugs provided intermediate of said recess, said lugs being adapted to form a strap receiving slot, and bent over the end of the 80 strap in order to permanently lock same thereto; a lug inwardly projecting from the lower edge of the aforesaid recess, suitably distanced from said other lugs, a part of said plate between said last named lug and 85 said other lugs being cut out, whereby a passage is formed intermediate of the lower edge of said plate; said inwardly projecting lug forming a locking element at the bottom or lower edge of the aforesaid recess, so as 90 to retain the looped end of said strap and prevent the displacement of the same, substantially as described.

Signed at Quebec, Quebec, Canada, this 23rd day of February, 1921.

THEODE GARCEAU.
